ATTORNEY.

UNITED STATES PATENT OFFICE.

DANIEL J. SCANLAN, OF ST. LOUIS, AND JOHN JOS. KEANE, OF ST. LOUIS COUNTY, MISSOURI, ASSIGNEES OF ONE-FIFTH TO KATHRYN A. CLEARY, OF ST. LOUIS COUNTY, MISSOURI.

DRAFT REGULATOR.

Application filed January 22, 1923. Serial No. 614,100.

To all whom it may concern:

Be it known that we, DANIEL J. SCANLAN and JOHN J. KEANE, citizens of the United States, the said DANIEL J. SCANLAN residing at the city of St. Louis, in the State of Missouri, and the said JOHN J. KEANE in the county of St. Louis, in the State of Missouri, have invented certain new and useful Improvements in Draft Regulators, of which

10 the following is a specification.

The object of this invention is automatically to control the combustion within a furnace or the like, so that it will not require personal human attention and so that the increase of heat will automatically close the draft and thus tend to retard combustion and so that the decrease of temperature resulting from the said retardation of combustion will automatically reopen the draft 20 and cold-air inlet and increase combustion.

This invention as designed is especially applicable to hot-air heaters, but is not confined thereto.

In the accompanying drawings forming 25 part of this specification, in which like numbers of reference denote like parts wherever they occur.

Figure 1 is a side elevation;

Figure 2 is a sectional view through a 30 hot-air pipe and showing this device located therein and with its external connections;

Figure 3 is a sectional view on a smaller scale, taken on the line 3—3 in Figure 2;

Figure 4 is a detail on an enlargement 35 scale of the regulating plate; and

Figure 5 is a side elevation on a smaller scale and perpendicular to the side elevation of Figure 1.

The diaphragm 1 is a hollow member and 40 contains a liquid, preferably water, that is readily expansible or contractible with the increase or decrease of heat of the adjacent atmosphere or solid bodies in contact with or in juxtaposition to the said diaphragm 1.

45 This diaphragm 1 is preferably made of copper or other suitable material arranged in pleats, so that when in its contracted form its longitudinal extension is materially less than when it is distended by the expansion within it of its liquid contents. When distended the pleats may be almost ironed out, so to speak; but in its contracted form the

pleats lie upon each other. This alternate contraction and distention resembles an accordian.

55 In a system of heating by hot air the diaphragm 1 is preferably located in one of the hot-air pipes 2, and for that purpose suitable means of support must be provided, such, for instance, as the hanger 3 suitably attached at its ends 4 to the interior of the said pipe 2 and preferably supported by any suitable support 4.

Diaphragm 1 is held in place upon hanger 3 by lugs 5 or other suitable means.

65 A tubular guide 6 receives a rod 7, upon one end of which is preferably attached a plate 8 in inner contact with or attached to some part of the diaphragm 1. By this means, when diaphragm 1 expands, plate 8 and rod 7 are pressed outward through opening 9 in pipe 2, to the furthestmost position shown in Figure 2; but when diaphragm 1 contracts gravity and spring 10 cause the lowering of rod 7 and plate 8 to the inner 70 position. Upon the other end of rod 7 is mounted a block 11, which in Figure 2 is shown in full-line and dotted-line positions, according to whether the diaphragm 1 is expanded or contracted.

80 A pitman 12 is attached at 13 to block 11 and is pivoted at 14 to a bracket 15 preferably mounted upon the outside of pipe 2.

The other end of pitman 12 is provided with a hook or finger 16, adapted to fit in 85 any one of the holes 17 in regulation plate 18, the lower end of which is connected by the chain 20 to the draft-door 21. The upper end of regulation plate 18 is connected by the chain 22 to the check-draft door 90 23, which is pivoted at 24 to the chimney-pipe 25. The chain 26 connects the check-draft door 23 with lever 27, which is pivoted at 28 to operate a damper 29 located in cold-air intake-pipe 30, which leads to the exterior of the building.

95 The chain 22 is supported by rolls 31 in hangers 32, which are secured to ceiling 33.

The chains 20, 22, and 26 are of such respective lengths as to be just taut when draft-door 21, check-draft door 23, and damper 29 are simultaneously in closed positions, as shown in Figure 5.

100 The draft-door 21 is made as light as pos-

sible, the combined weight of the check-draft door and the damper arm 27 being great enough to overcome friction and the weight of the draft-door.

- 5 The operation of the device is as follows: When the diaphragm 1 expands, the rod 7 is pushed outwardly and likewise the block 11. This causes pitman 12 to rock on pivot 14, whereby the end bearing hook 16 is depressed, thus allowing plate 18 and chain 20 to descend. When the plate 18 has descended through a certain portion of its stroke, the draft-door 21 is brought to its closed position, as shown in Figure 5, thus 15 cutting off the supply of air to the fire. In this position the check-draft door 23 and the damper 29 are still closed. This is important, as the check-draft door must not be opened until the supply of air to the fire has 20 been cut off.

As the diaphragm continues to expand, chain 20 becomes slack, and the check-draft door 23 and the damper 29 are next opened simultaneously by the pull on the chains 22 25 and 26. This action simultaneously checks the draft at the chimney and, also, admits cold air from outdoors through pipe 30 into the furnace. This cold air is supplied in addition to the warmer air coming in from 30 the basement through opening 34. The now greater difference of temperature between the incoming cold air and the outgoing hot air causes an increased flow of hot air through the pipes 2. This is desirable, for 35 if no cold outside air is supplied when the fire is checked the hot air within the furnace becomes stagnant when the furnace has cooled, because of the smaller temperature difference between the warm incoming 40 basement air and the slightly hotter outgoing air.

When the furnace cools, the temperature decreases in the pipe 2 and this results in the contraction of the diaphragm 1. This 45 results in the lowering of rod 7 and block 11 whereby pitman 12 rocks upon pivot 14, automatically elevating hook 16 and plate 18, and closing the damper 29 and the check-draft door 23, and taking the slack of chain 20. As the diaphragm continues to contract, plate 18 is elevated still more, whereby 50 the draft-door 21 is automatically opened by the rising chain 20, thus re-establishing the draft. The furnace 35 is thus caused to give forth more heat, which eventually when 55 needed again expands diaphragm 1 and in succession a repetition of the closing of

draft-door 21 and the opening of check-draft door 23 and damper 29.

Plate 18 contains a plurality of notches 60 or holes 17, so as to provide for adjustability, which adjustability is useful for changes of atmospheric temperature due to the weather and such changes as may be due to age of parts and other temporary or permanent conditions.

Having thus described this invention, we hereby reserve the benefit of all changes in form, arrangement, order, or use of parts, as it is evident that many minor changes 70 may be made therein without departing from the spirit of this invention or the scope of the following claims.

We claim:

1. In a device of the type described, the combination with a tubular structure, of a cradle-shaped structure having a leg depending from the base thereof formed integrally with and extending transversely of said tubular structure, an expansible 80 chamber removably secured within said cradle-shaped structure, a stem connected to said chamber and extending outwardly of said tubular structure, a lever mounted exteriorly of said tubular structure and pivotally connected to said stem, and means within said chamber affected by the change of temperature within the tubular structure for axially varying the expansible chamber 85 to operate said lever.

2. In a device of the type described, the combination with a tubular structure, of a cradle-shaped structure having a leg depending from the base thereof formed integrally with and extending transversely of said tubular structure, an accordion-shaped chamber 90 removably attached to the base of said cradle-shaped structure, a stem connected to said chamber and extending outwardly of said tubular structure, a spring interposed between said tubular structure and a shoulder on said stem for exerting a force to compress said chamber, a lever pivotally mounted exteriorly of said tubular structure and connected to said stem, and a fluid positioned 100 within said chamber and affected by the change of temperature within the tubular structure for axially expanding the chamber 105 to operate said lever.

In testimony whereof we hereunto affix 110 our signatures.

DANIEL J. SCANLAN.
JOHN JOS. KEANE.
